JULIA C. PHILLIPS, OF NEW YORK, N. Y.

KITCHENETTE.

Application filed November 7, 1924, Serial No. 748,376. Renewed December 28, 1928.

This invention relates to convertible furniture and particularly to a portable kitchenette, designed, when not in use, to simulate a cabinet, table or other article of living room or bedroom furniture.

In the one or two room apartment space is always at a premium, and the problem of cooking, if only in a small way, not easily solved. And even where the need for space is not so exigent, occasions often arise when one wishes to prepare a meal in the living room or the bedroom; breakfast in bed for the hale and hearty is a treat, while for the invalid, hot food cooked at the bed-side may have a real therapeutic value. In accordance with the present invention, I have designed a kitchenette which solves the cooking problem in the small apartment and which is especially adapted for use in bedrooms. This kitchenette is built in the form of a table or cabinet, which when closed and serving no culinary purpose, looks for all the world like any other well-dressed respectable piece of living room or bedroom furniture, but which when opened reveals its true utilitarian inwardness. The one-time table top folds back, and, supported by a bracket or gate-leg, forms a sizable table, so designed that it may extend over a bed in suitable position for use. Immediately below the former position of the top, we find the kitchen proper, an enamel-lined compartment equipped with electric connections for grill, toaster, percolator, etc., and provided with a tray bottom, preferably of enamelled metal, readily removable for cleaning. What appeared to be the outer face of the upper drawer of the table swings down and forms an extension of the bottom of the cooking compartment, while the lower drawer may serve as cupboard and pantry.

In order that the invention may be more clearly understood, I have illustrated a preferred embodiment thereof in the accompanying drawings, in which Fig. 1 is a perspective view of a kitchenette constructed in accordance with the present invention in condition for use, with the table top shown extended over a bed; and Fig. 2 is an elevation of this kitchenette when not in use as a kitchenette.

When in closed position, as shown in

Fig. 2, the kitchenette resembles a cabinet, table or chest of drawers, and comprises a body portion 1 supported upon legs 2, and provided with a top 3, and apparently provided with two drawers, 4 and 5. At the left hand side of the table, as shown in Fig. 2, there is provided a gate-leg 6, which folds against the side of the table when not in use. When it is desired to use the table as a kitchenette, this gate-leg is swung outwardly into the position shown in Fig. 1, and the top 3 of the table swung into horizontal open position. At the same time, the outer face of what appeared to be the upper drawer 4 is swung down into horizontal position, all as clearly shown in Fig. 1.

When the top 3 and the drop-leaf drawer front 4 are in open position the cooking compartment 7 or kitchen proper is discovered. This compartment is lined with enamelled iron and is provided with a tray bottom 8 which can be readily removed for cleaning. This tray is provided at its sides and rear with an upstanding flange 9 designed to make a snug fit with the side walls of the compartment. The drop leaf drawer front 4 when in its open position constitutes an extension of the bottom of the cooking compartment. An electrical connection 10 is mounted upon the rear wall of the cooking compartment and is suitably wired to a cord 11 of sufficient length to make connection with a floor plug or any suitable or convenient source of electricity. The lower drawer or drawer proper 5 may be utilized for the storage of food and cooking utensils.

The height of the table is such that when the table top 3 is in open position, it is just the right height to extend over a bed and permit the occupant to use it as a table. At the same time, the cooking compartment is readily available and can be used by the occupant of the bed in the preparation of the meal. By having a wired multiple outlet fixed within the cooking compartment, the various electrical heating means usually employed in the preparation of a meal can be readily attached and detached without the awkward necessity for cords extending into the compartment. By lining the compartment with enamel metal or similar heat and water resistant material, and by mak-

ing the movable tray of the same material, therein, a gate-leg mounted at one end of it is possible to keep the cooking compartment clean, fireproof and sanitary. When above said gate-leg and adapted to close the not in use, the kitchenette is entirely compartment, and a drop-leaf 5 concealed and the table can be used for other hinged to said cabinet at one side of said purposes without in any way disfiguring compartment and adapted to close the same. the room. 15

I claim:

A kitchenette cabinet comprising a body 10 portion having a cooking compartment

In testimony whereof I affix my signature.

JULIA C. PHILLIPS.
